UNITED STATES PATENT OFFICE

LUIS M. VALBUENA, OF NEW YORK, N. Y.

DENTAL PLATE

Application filed January 9, 1931. Serial No. 507,541.

This invention relates to an improvement in dental plates, the embodiment thereof being preferably associated with the type of artificial denture having a relatively small holding or seating surface.

I am aware that dental plates heretofore have been constructed to include a suitable suction chamber and a means for creating and maintaining a vacuum therein in order 10 to hold the plate against the walls of the mouth.

The disadvantages of such a construction are that the soft tissue of the mouth is thereby drawn into the vacuum chamber and distorted from its normal form to take a shape corresponding to the suction chamber, that the soft tissue within the chamber prevents an even distribution of the suction or holding effort and that the plate, being maintained by 20 the surface of the tissue alone, is not positioned with sufficient rigidity to prevent it from shifting crosswise in the mouth during use, causing considerable discomfiture to the wearer.

25 The primary object of my invention, therefore, is to provide a dental plate construction to obviate the above disadvantages.

In accomplishing this feature of the invention provision is made for a plurality of supporting projections located within the suction or vacuum chamber of the dental plate and which are adapted to conform with the shape of the corresponding tissue of the mouth. The tips of the supporting projections are therefore made to conform with the portion of the mouth tissue against which they are to fit. In this manner the gum or 35 soft tissue is not drawn any appreciable distance into the suction chamber.

40 A further object is to provide a novel valve construction which will permit the creation of the desired negative pressure within the vacuum chamber and prevent air leakage to the same so that practically no attention 45 need be given to the plate by the wearer after its installation.

50 My invention further includes other objects, advantages and novel features of construction hereinafter more particularly referred to and which will be apparent from

the accompanying drawing in which I have illustrated the preferred embodiment of the same.

In the drawing Figure 1 is a side elevation of the improved dental plate.

Fig. 2 is a plan view of the plate as illustrated in Figure 1.

Fig. 3 is a section on line 3—3, Fig. 2.

Fig. 4 is a section on line 4—4, Fig. 2, and

Fig. 5 is an enlarged sectional elevation of 60 one of the teeth of the plate showing the valve construction therein.

Referring to the drawing the body of the plate is indicated at 10, the outer portion of the same being shaped in the usual manner 65 to conform with the dental arch and irregularities of the mouth of the person to be fitted.

The tapering inner sides of the body of the plate are indicated at 11 and 12, the same defining with the lower surface of the plate 70 13 an open chamber 14, which extends substantially about the entire upper portion of the denture, and into which the tissue of the mouth fits. Extending from the base or bottom portion of the chamber 14 are a plurality 75 of supporting projections as indicated at 15, the same being preferably included as an integral rigid portion of the body of the plate.

The projections vary in height and curvature of tip surface, each particular projection 80 being adapted to fit against a given portion of the mouth to maintain the same therein in a natural manner. For purposes of illustration the projections are shown in a circular form and the tips of the same are curved, as indicated at 16, to fulfill the requirements of 85 the instant case, although obviously the shape or structural form of the respective projections may be varied without departing from the nature and spirit of the invention.

Inasmuch as the form of each projection in the plate is determined by the structure of the mouth against which it is adapted to fit, it is apparent that the projections need not be evenly distributed along the base of the chamber 95 14 but may be placed as needed for the denture being constructed. The tips of the projections support the tissue and prevent the same from being drawn into the lower portion of the chamber 14. This construc- 100

tion also by holding the tissue from the base of the chamber enables the distribution of negative pressure or holding effort to uniformly affect the under surface of the same and thereby maintain the plate firmly in position.

The projections fitting against the firm portion of the mouth tissue prevent the plate from rocking or shifting crosswise in the mouth during use. A centering support 17 extends from the inner front portion of the plate to take a position within the chamber 14, the same assisting and acting in a similar manner as the projections 15 to consequently give an additional measure of support to prevent the shifting of the plate in the mouth. The portion of the plate below the tip surfaces of the projections 15 forms a suction chamber in which a negative pressure can be created as will hereinafter be more particularly described.

Referring particularly to Figs. 3 and 5, the plate is provided with suitable vertical openings or passageways 18 and 19 extending from the base 13 or lower portion of the suction chamber and making communication with the corresponding horizontally located openings or cavities 20 and 21 in two oppositely disposed teeth of the denture. Inasmuch as the respective teeth containing this construction are substantially identical but one of the same will be described in detail. The larger of the artificial teeth, preferably the molars, are utilized so that a sizable opening may be formed therein without weakening the structure.

As clearly indicated in Fig. 5 the horizontal opening 21 extends from the inner side of the tooth so that a suction created by the wearer can directly control a device situated therein. The device illustrated forms a controlling mechanism or one way valvular element for normally closing communication between the passage 18 and opening 21 and permit the same on the creation of a vacuum in the mouth of the wearer to open the valve so that a partial vacuum can be created in the suction chamber of the denture. This valvular construction is preferably formed by a hollow cylindrical tubing 22 of an elastic substance such as rubber. The exposed end portion of the tubing 22 which is substantially flush with the surface of the teeth is provided with an integral cap or head 23 having a central pin hole opening therein as illustrated at 24. The purpose of the cap on the tubing is to prevent particles of food taking position within the opening in the tooth.

In positioning the plate the wearer produces a partial vacuum or suction which initially draws the air from the central portion of the tubing 22 through the pin hole opening 24 and causes the same to contract circumferentially and take the position shown by the dotted lines in Fig. 5. This di-

rectly opens communication between the mouth and suction chamber around the outer edge or periphery of the tubular member 22 as shown at 25. When the desired negative pressure or holding effort is obtained in the suction chamber the tubing 22 returns to its normal position against the passageway 18 by the release of the pressure in the mouth, and maintains this effort within the suction chamber as long as desired.

While the plate illustrated in the drawing and herein described is adapted for use in the upper portion of the mouth obviously large partial plates or plates fitting the lower portion of the mouth can be constructed fulfilling the inventive concepts described herein without departing from the nature and spirit of the invention.

I claim as my invention:

1. In a dental plate, a suction chamber containing tissue supporting projections located, therein, and provided with a vertical air passageway extending from the base of the suction chamber to communicate with a horizontal cavity in one of the teeth of the denture, a circumferentially contractable valvular element situated within the horizontal cavity and including a pin-hole opening at its exposed surface to facilitate the initial withdrawal of air from the interior of the valvular element, whereby, the withdrawal of air from the suction chamber around the periphery of the valvular element is facilitated upon the creation of a partial vacuum in the mouth.

2. In a dental plate, a suction chamber having a plurality of tissue supporting projections located, therein, and provided with an air passageway extending from the base of the suction chamber to communicate with a cavity in one of the teeth of the denture, a circumferentially contractable tubular member situated within the cavity and including a pin-hole opening at its exposed surface to facilitate the initial withdrawal of air from the interior of the tubular member, whereby, the withdrawal of air from the suction chamber around the periphery of the tube is facilitated upon the creation of a partial vacuum in the mouth.

3. In a dental plate, a suction chamber having a plurality of tissue supporting projections located, therein, and provided with an air passageway extending from the base of the suction chamber to communicate with a horizontal cavity in one of the teeth of the denture, a circumferentially contractable tubular member situated within the cavity and including a pin-hole opening at its exposed surface to facilitate the initial withdrawal of air from the interior of the tubular member, whereby, the withdrawal of air from the suction chamber around the periphery of the tube is facilitated upon the creation of a partial vacuum in the mouth, said tubu-

lar member having an end portion substantially closing the cavity at the surface of the tooth.

4. In a dental plate, a suction chamber containing tissue supporting projections located therein, and provided with a vertical air passageway extending from the base of the suction chamber to communicate with a horizontal cavity in one of the teeth of the denture, a circumferentially contractable 10 valvular element situated within the horizontal cavity and including a pin-hole opening at its exposed surface to facilitate the initial withdrawal of air from the interior of the 15 valvular element, whereby, the withdrawal of air from the suction chamber around the periphery of the valvular element is facilitated upon the creation of a partial vacuum in the mouth, said valvular element having 20 an end portion substantially closing the cavity at the surface of the tooth.

5. In a dental plate having a suction chamber for holding the same in position in the mouth, one or more air passageways extending 25 from the lower portion of the suction chamber to communicate with a cavity located in or more teeth of the denture, each cavity containing a circumferentially contractable tubular member, therein, having an end 30 closing portion substantially flush with the surface of the tooth, said end portion having a pin-hole opening to facilitate the initial withdrawal of air from the interior of the tube, whereby, the withdrawal of air from 35 the suction chamber around the periphery of the tubular member is facilitated upon the creation of a partial vacuum in the mouth.

6. In a dental plate having a suction chamber for holding the same in position in the 40 mouth, one or more air passageways extending from the lower portion of the suction chamber to communicate with a horizontal cavity located in one or more teeth of the denture, each cavity containing a circumfer- 45 entially contractable valvular element, therein, having an end closing portion substantially flush with the surface of the tooth, said end portion having a pin-hole opening to facilitate the initial withdrawal of air from the 50 interior of the valvular element, whereby, the withdrawal of air from the suction chamber around the periphery of the valvular element is facilitated upon the creation of a partial 55 vacuum in the mouth.

7. In a dental plate having a suction chamber for holding the same in position in the mouth, an air passageway from said suction chamber communicating with a cavity in one 60 of the teeth of the denture, a contractable valvular element, located in said cavity, the periphery of which controls communication between the suction chamber and mouth, and means for initially withdrawing the air from 65 the interior of the valvular element to facili-

tate its operation upon the creation of a partial vacuum in the mouth.

8. In a dental plate having a suction chamber for holding the same in position in the mouth, an air passageway from said suction 70 chamber communicating with a cavity in one of the teeth of the denture, a contractable tubular member, located in said cavity, the periphery of which controls communication between the suction chamber and mouth, said 75 tubular member having an end portion substantially closing the cavity at the surface of the tooth, and means for initially withdrawing the air from the interior of the tubular member to facilitate its operation upon 80 the creation of a partial vacuum in the mouth.

Signed by me this 6th day of January, 1931.
LUIS M. VALBUENA.
